FOOTBALL JERSEY HAVING HAND-HOLDS
Donald T. Corbett, 4706 W. Harrison St., Chicago 44, Ill.
Filed Sept. 26, 1958, Ser. No. 763,631
2 Claims. (Cl. 2—90)

This invention relates to an improved football jersey having hand-hold means.

The primary object of the invention is to provide hand-hold means on football jerseys arranged to be grasped by the hands of offensive blockers while blocking so that neither of the hands is free to deliberately or inadvertently and illegally grasp and hold defensive players, so that holding penalties are prevented.

Another object of the invention is to provide hand-hold means of the character indicated above, which are preferably in the form of straps, and which are detachably secured to a foot-ball jersey so that they will become detached from the jersey, if grasped and pulled by a tackler, so that they cannot be availed of as handles in tackling or in holding the wearer of the jersey.

A further object of the invention is the provision of hand-hold straps of the character indicated above which can be made in rugged and serviceable forms at relatively low cost, which do not add objectionably to the overall cost of football jerseys, which do not interfere with the laundering of the jersey, and which present no inconvenience or burden to a football player.

Other important objects and advantageous features of the invention will be apparent from the following description and the accompanying drawings, wherein, for purposes of illustration only, a specific form of the invention is set forth in detail.

In the drawings:

FIGURE 1 is a perspective view of a football player grasping hand-hold means on a jersey in accordance with the present invention;

FIGURE 2 is an enlarged front elevation of a jersey having hand-hold straps thereon; and

FIGURE 3 is a further enlarged fragmentary vertical transverse section taken on the line 3—3 of FIGURE 2.

Referring in detail to the drawings, wherein like numerals designate like parts throughout the several views, the illustrated football jersey, generally designated 10, shown being worn by a football player 12 having hands 14, comprises a front panel 16 and is otherwise conventionally formed. However, it is to be understood that the present invention contemplates any other form of football shirt or other garment worn during play and having a front panel 16 across which the player's hands 14 are placed, in offensive blocking position, with the elbows at the sides. Also, the present invention contemplates any suitable form of hand-hold means, to be grasped by the hands 14 in these positions, which are detachably secured to a front panel 16, with sufficient security to hold the hands in these positions under playing conditions, but are detachable from the panel 16 by a pull exerted thereon by an opposing player, strong enough to unbalance or throw the wearer of the hand-hold means.

As will be apparent from the drawing, the jersey 10 has a closely-embracing body portion which is adapted to extend from the neckline to below the waistline, and on the front panel 16 of the body portion are a pair of vertically-arranged laterally-spaced hand-hold straps 18, the straps being positioned on each side of the front

2

panel and being of a length to extend from the upper chest-covering portion of the front panel to a point adjacent the waistline of the front panel. The straps 18 are adapted to support the arms from the body of an athlete when wearing the jersey and engaged in contest play.

The illustrated hand-hold means, generally designated 18, comprises a pair of similar, vertically elongated flexible straps 20, which are preferably made of such strong and washable material as army belt fabric. The straps 20 have end portions 22 which are turned over and suitably secured, as indicated at 24, as by sewing to the back 26 of the strap 20, as reinforcements at the ends of the effective lengths of the straps 20, and as retaining and insulating means for the female components 28 of separable snap fasteners 30, which are securably engageable with male components 32 secured to the jersey front panel 16. As shown in FIGURE 2, the straps 20 are preferably arranged parallel to each other at side points of the panel 16 in the chest covering area thereof.

As shown in FIGURE 3, the female fastener components 28 having reduced shanks 34 which extend rearwardly through openings 36 provided in the turned over strap end portions 22, and have lateral annular flanges 38 thereon which bear against the rear sides of the portions 22, in opposition to enlarged heads 40, on the forward ends of the shank 34, which are confined between the forward sides of the portions 22 and the rear or back side 26 of the strap 20. Portions 42 of the strap 20 conformably overlying the heads 40 serve to insulate the heads 40 from injurious and wearing external contacts and protect the heads 40 during laundering or other cleaning of the straps 20. The shanks 34 terminate at their rear ends in spring sockets 44 for securable reception of the male fastener components 32.

The male components 32 preferably comprise shanks 44 which extend through openings 46 and 48 provided respectively in the front panel 16 and in a reinforcing patch 50, which is of suitable material, such as leather, and is suitably secured, as by sewing 52 to the inner or rear side of the front panel 16, in a manner to prevent pulling out or loosening of the male components 32. The shanks 44 have enlarged flat heads 54 on their rear ends, which bear against the rear sides of the patches 50, enlarged flat collars 56, which bear against the forward side of the front panel 16, and terminate at their forward ends in knobs 58 for engaging in the female component sockets 44. It will be understood that any other suitable and adequate separable fastening means for securing the strap ends to the front panel 16 are contemplated by the present invention.

With an offensive blocker's hands 14 grasping the straps 20, as shown in FIGURE 1, the hands and the players arms and elbows are held in legal offensive blocking positions, and the hands while so maintained are not free to commit inadvertent offensive acts which can subject the player's team to penalties. Further, the difficulty and fatigue involved in maintaining correct offensive blocking positions of the hands, arms, and elbows are reduced.

Although there has been shown and described herein a preferred form of the invention, it is to be understood that the invention is not necessarily confined thereto, and that any change or changes in the structure of and in the relative arrangements of components thereof are contemplated as being within the scope of the invention as defined by the claims appended hereto.

What is claimed is:

1. A football jersey adapted to be worn by an athlete when engaged in contest play and having a closely-embracing body portion adapted to extend from the neckline to below the waistline, said body portion having a front panel, a pair of vertically-arranged laterally-spaced hand-hold straps positioned on said front panel on each side thereof and having their upper and lower ends secured to said panel, said straps being of a length to extend from the upper chest-covering portion of said front panel to a point adjacent the waistline of said front panel and being adapted to support the arms from the body of an athlete when wearing said jersey and engaged in contest play.

2. The jersey according to claim 1, wherein the upper and lower ends of said straps are releasably secured to said front panel.
